PARASITICIDAL COMPOSITION

Joseph N. Borglin, Wilmington, Del., assignor to
Hercules Powder Company, Wilmington, Del., a
corporation of Delaware

No Drawing. Application August 17, 1939,
Serial No. 290,634

16 Claims. (Cl. 167—24)

This invention relates to an improved parasiticide composition and more particularly to an improved parasiticide composition containing a terpin lower fatty acid ester.

It is an object of this invention to provide parasitides of high killing power to insects and similar pests. It is an object to provide such compositions having little or no effect upon the warm-blooded animals.

It is a further object to provide parasitoidal compositions of wide range of possible formulation so that compositions for many purposes can readily be prepared from a few materials at low cost.

It is a still further object to provide effective 15 parasitoidal compositions such as contact insecticidal sprays low in odor.

It is a still further object to enhance greatly by activation the effectiveness of the expensive plant body toxic agents such as rotenone, pyrethrum extract, etc.

The composition in accordance with this invention will comprise a terpin lower fatty acid ester and a diluent which may be another insecticide, an inert carrier material or a mixture of another insecticide and an inert carrier. The terpin lower fatty acid ester may be, for example, terpin diacetate, terpin dipropionate, terpin dibutyrate, etc., or it may be a chemically mixed ester such as terpin aceto-butyrate, terpin aceto-propionate, terpin butyropropionate, etc. The esters of any of the terpin forms, i. e. 1:8 terpin or 1:4 terpin, may be utilized.

The inert carrier selected for use in the composition according to this invention may be varied depending upon the method of application by which, and the purpose for which, the composition will be ultimately used. The composition in accordance with this invention can be used in the form of a spray, a dusting powder or as a paint or gum. The inert carrier used in a composition intended for application as a spray will be a liquid of the type commonly used as a carrier liquid in parasiticide compositions such as, for example, water, suitable petroleum hydrocarbons, etc., as ordinary or deodorized kerosene, etc. Moderately volatile liquids are usually preferred as carriers for sprays. The inert carrier used in compositions intended for application as a dust will be a finely divided solid of the type commonly used as a carrier for insecticidal dusts such as, for example, talc, colloidal clays, Bentonite, fuller's earth, sulphur, etc. The carrier in compositions intended for use as a paint or gum may be a natural or residual asphalt.

Compositions for application as a spray may be utilized in the form of a solution, emulsion, or suspension. Such compositions will comprise one or more lower fatty acid esters of terpin dis-

solved in an inert carrier liquid which is a solvent therefor, for example a petroleum fraction or modified petroleum fraction such as deodorized or ordinary kerosene, etc. Such compositions are suitable for use in the control of insects, such as flies, mosquitoes, roaches, spiders, bed bugs, fleas, silver fish, centipedes, and other insects and insect-like animals, all of which are included in the term "parasite", as used herein and in the claims. A typical composition of this type will consist of the terpin ester dissolved in deodorized kerosene, the terpin ester being in an amount within the range of about 0.5% to about 75% by weight of the composition.

Compositions for application as a spray may also be utilized in the form of an aqueous emulsion. Such compositions will comprise the terpin lower fatty acid ester which may be either emulsified directly in water or dissolved in a water-immiscible solvent with or without other parasitoidal agents, and the solution thus formed emulsified in water. Such emulsions will desirably contain emulsifying agents such as, for example, a soap, a sulfonated oil, etc. They may be prepared in completely finished form at the point of manufacture or they may be prepared in the form of a concentrate comprising the terpin ester and an emulsifying agent, and then diluted and emulsified with water at the point of application, thus avoiding the unnecessary packaging, transportation and handling of water. Emulsified compositions of this type are advantageous for the destruction of parasites attacking horticultural plants such as, for example, the various kinds of plant lice, mealy bugs, thrips, aphids, the various kinds of scale, etc., all of which are included in the term "parasite", which gives rise to the term "parasitoidal", as used herein and in the claims.

The parasitoidal compositions in accordance with this invention may also be used for the destruction of insects which attack agricultural or horticultural plants in the form of insecticidal dust. Terpin diacetate or other lower fatty acid ester, either alone or admixed with other toxic insecticidal materials, will be thoroughly admixed, for example, by trituration, with a powdered solid material of the type commonly used for insecticidal dusts to produce such an insecticidal dust. A typical composition of this type is, for example, talc, ground to 200 mesh and incorporated with from about 0.5% to about 45% by weight of the terpin ester. Similarly the terpin ester may be incorporated with comminuted derris root, cube root, tobacco, timbo root, pyrethrum flowers, etc. The quantity of the terpin ester incorporated into the insecticidal dust is limited only by the ability of the dust to absorb it without caking, i. e., ground

cube root can absorb up to about 45% terpin ester without caking.

The lower fatty acid esters of terpin have the property of activating other parasiticidal materials. This is especially noticeable when they are used to activate toxic extracts such as from pyrethrum flowers, derris root, cube root, tobacco, etc., i. e. pyrethrins, rotenone, nicotine compounds, etc. Many of these toxic agents have a fairly good stunning power without the ability to impart by themselves a satisfactory high kill of the insects acted upon. When terpin lower fatty acid esters are added thereto, a high killing power results, all out of proportion with the killing power of the components taken separately.

The terpin ester, terpin diacetate, for example, which I utilize may be prepared by reacting terpin, conveniently 1:8 terpin, with acetic anhydride in the presence of sodium acetate or other suitable catalyst at a temperature within the range of about 60° C. to about 175° C. by the process disclosed and claimed in the copending application of J. N. Borglin, Ser. No. 267,913, filed April 14, 1939. The preparation of other lower fatty acid esters in an analogous manner is also disclosed therein.

The compositions in accordance with this invention are further illustrated by the formulae for compositions suitable for application as a spray, given in Table 1 which follows:

Table 1

	I	II	III	IV	V	VI	VII	VIII	IX
Terpin lower fatty acid ester	Percent 10	Percent 10	Percent 10	Percent 5	Percent 5	Percent 5	Percent 5	Percent 5	Percent 40
Pine oil	5	2						90	
Kerosene	90	85		94	94	94		5	60
Glycol ether of pinene				1.0				0	
Pyrethrum					1.0				
Rotenone						1.0	1.0		
Nicotine			2.0				2.0		
Sodium oleate				86.0			92		
Water									

In the above compositions III and VII, the sodium oleate functions to disperse the water-immiscible parasiticides in water. Other emulsifying agents which may be used for this purpose are, for example, the alkali metal salts of the higher alkyl sulfates, as, sodium lauryl sulfate, sodium oleyl sulfate, etc., the alkali metal salts of sulfated abietyl or hydroabietyl alcohol, sulfonated pinene-phenol condensate, alkali metal resinates, such as sodium rosinate, etc., other alkali metal soaps, as sodium palmitate; sodium stearate, etc.

Example of insecticidal powders in accordance with this invention are shown in Table 2 which follows:

Table 2

	X	XI	XII	XIII	XIV
Terpin lower fatty acid ester	Percent 10	Percent 25	Percent 15	Percent 15	Percent 10
Pulverized sulfur	5	75	60		
Kieselguhr	85	85	12.5	12.5	90
Ground cube root					

Table 3 shows data as to the toxicity of dif-

ferent samples of terpin esters to house flies as measured by the Peet-Grady test:

Table 3

	Material used	Concentration in deodorized kerosene	Toxicity to house flies as measured by Peet-Grady test	
			Knocked down	Dead in 24 hours
15	Terpin diacetate (sample A)	Percent 2.5	Percent 49	Percent 12
	Terpin diacetate (sample A)	5.0	55	15
	Terpin diacetate (sample B)	2.5	61	10
	Terpin diacetate (sample B)	5.0	73	17
	Terpin diacetate (sample C)	5.0	69	17
	Terpin diacetate (sample C)	10.0	77	61
	Terpin dibutyrate	5.0	52	15

Table 4 gives data as to the toxicity to house flies by the Peet-Grady test of insecticides for comparison, similar data is given for the National Association of Insecticide and Disinfectant Manufacturers' Official Test Insecticide, which consists of pyrethrum in deodorized kerosene. The terpin diacetate insecticides listed in Table 4 were made simply by adding the specified quantity of terpin diacetate to the Official Test Insecticide.

Table 4

	Insecticide	Toxicity to house flies as measured by the Peet-Grady test	
		Knocked down	Dead in 24 hours
50	Official test insecticide (pyrethrum extract in deodorized kerosene)	96	24
55	Official test insecticide plus 2.5% terpin diacetate	98	49.8
60	Official test insecticide plus 3% terpin diacetate	99	56
	Official test insecticide plus 5% terpin diacetate	99	63.5

The data in Table 4 demonstrate the high killing power obtained by the combination of terpin lower fatty acid ester and pyrethrum. Inspection of the data given in Tables 3 and 4 will further show that the combination of terpin diacetate with pyrethrum has a killing power greater than what would be obtained by the addition of the killing power of the two components taken separately. The terpin diacetate thus has an unexpected activating influence upon pyrethrum, the reason for which is not known. Similar activation occurs with rotenone, nicotine and the like and, in fact, so far as is known, with any

Contact parasiticide, including not only those existing in or extracted from plant bodies but the various synthetic agents such as the various thiocyanates, etc.

Activation is also brought about by other lower fatty acid terpin esters, for example, terpin dипropionate. Table 5 gives toxicity data for a fly spray consisting of a pyrethrum extract in deodorized kerosene, and the same spray after addition of 3% of terpin dипropionate:

Table 5

	Pest-Grady toxicity test	
	Knocked down	Dead in 24 hours
Per cent	Per cent	
Spray (A) pyrethrum extract in deodorized kerosene	99	48
Spray (B) 3% terpin dипropionate added to spray (A)	99	67.4

Spray (B) rates as a Grade AA insecticide or better. The effect of the small addition of terpin dипropionate is chiefly by reason of its activation of the pyrethrum.

The parasiticides in accordance with this invention have the advantage of very low odor, at most a slight, sweet, ester odor. In this respect they are superior to parasiticides containing organic sulphur compounds, which have a mercaptan odor. Further, they do not irritate the eyes or nose when sprayed and have, so far as is known, no effect upon human beings, in ordinary use.

The low odor, which is for practical purposes no odor at all, and the complete absence of any irritational effect upon humans combined with the low cost, infinite miscibility in kerosene, stability, and absence of sludge formation of the terpin lower fatty acid esters, makes possible an unusually wide range of formulation of parasiticides. The quantity of active agent in the composition can be varied very widely according to the specific purpose of the material without encountering the usual limitations of insolubility, odor, and irritation. Thus, instead of the usual limitation of active ingredient in sprays 1 to 10%, the terpin fatty acid esters may be used in any quantity, say up to 50 or 75%.

It will be appreciated that the examples given hereinbefore represent simple formulations given in illustration. The common practice of using several different toxic agents in a single parasiticide to obtain maximum effectiveness for a wide variety of parasites may be followed in preparing compositions containing terpin lower fatty acid esters. The activating properties of the terpin esters are of particular value in such all-purpose compositions.

It will be understood that the details and examples given hereinbefore are illustrative only and in no way limiting on my invention as described broadly hereinbefore and in the appended claims.

What I claim and desire to protect by Letters Patent is:

1. An insecticidal composition comprising a terpin lower fatty acid ester and a diluent.
2. An insecticidal composition comprising a terpin lower fatty acid ester supported on a finely divided solid.
3. An insecticidal composition comprising a terpin lower fatty acid ester supported on a finely divided solid from the group consisting of comminuted derris root, cube root, tobacco, timbo root, and pyrethrum flowers.
4. An insecticidal composition comprising a terpin diacetate and a finely divided solid from the group consisting of comminuted derris root, cube root, tobacco, timbo root, and pyrethrum flowers.
5. An insecticidal composition comprising a terpin lower fatty acid ester and an inert carrier liquid.
6. An insecticidal composition comprising a terpin lower fatty acid ester, a toxic ingredient extracted from a plant body of the group consisting of derris root, cube root, timbo root, tobacco, and pyrethrum flowers, and a liquid petroleum fraction.
7. An insecticidal composition comprising a terpin diacetate, toxic ingredient extracted from a plant body of the group consisting of derris root, cube root, timbo root, tobacco, and pyrethrum flowers, and a liquid petroleum fraction.
8. An insecticidal composition comprising a terpin diacetate, toxic ingredients extracted from pyrethrum flowers, and a suitable liquid petroleum fraction.
9. An insecticidal composition comprising 1:8 terpin diacetate, toxic ingredients extracted from pyrethrum flowers, and a suitable liquid petroleum fraction.
10. An insecticidal composition comprising a terpin dипropionate, a toxic ingredient extracted from a plant body of the group consisting of derris root, cube root, timbo root, tobacco, and pyrethrum flowers, and a liquid petroleum fraction.
11. An insecticidal composition comprising a terpin dипropionate, toxic ingredients extracted from pyrethrum flowers, and a suitable liquid petroleum fraction.
12. An insecticidal composition comprising 1:8 terpin dипropionate, toxic ingredients extracted from pyrethrum flowers, and a suitable liquid petroleum fraction.
13. An insecticidal composition comprising a terpin lower fatty acid ester, a toxic ingredient extracted from a plant body of the group consisting of derris root, cube root, timbo root, tobacco, and pyrethrum flowers and an inert carrier liquid.
14. An insecticidal composition comprising a terpin diacetate, toxic ingredients extracted from pyrethrum flowers, and an inert carrier liquid.
15. An insecticidal composition comprising a terpin lower fatty acid ester, rotenone, and an inert carrier liquid.
16. An insecticidal composition comprising a terpin diacetate, rotenone, and an inert carrier liquid.

JOSEPH N. BORGLIN.

CERTIFICATE OF CORRECTION.

Patent No. 2,252,548.

August 12, 1941.

JOSEPH N. BORGLIN.

It is hereby certified that error appears in the printed specification of the above numbered patent requiring correction as follows: Page 2, second column, line 23, for the syllable "con--" read --containing pyrethrum and terpin diacetate. For--; page 3, second column, line 48, claim 12, for "insectidal" read --insecticidal--; and that the said Letters Patent should be read with this correction therein that the same may conform to the record of the case in the Patent Office.

Signed and sealed this 16th day of September, A. D. 1941.

Henry Van Arsdale,
Acting Commissioner of Patents.
